[57] CLAIM

The ornamental design for a billiard game table, as shown and described.

DESCRIPTION

FIG. 1 is a perspective view of a billiard game table showing my new design;
FIG. 2 is a top plan view thereof;
FIG. 3 is a front elevational view thereof; the rear elevational view being a mirror image thereof; and,
FIG. 4 is a left side elevational view thereof; the right side elevational view being a mirror image thereof. The bottom surface is plain and unornamented.

FIG. 1

FIG. 2

FIG. 3

FIG. 4
